UNITED STATES PATENT OFFICE.

ELIZABETH SHEETS, OF CASSTOWN, OHIO.

FRUIT-DRIER.

SPECIFICATION forming part of Letters Patent No. 288,503, dated November 13, 1883.

Application filed June 6, 1883. (No model.)

To all whom it may concern:

Be it known that I, ELIZABETH SHEETS, of Casstown, in the county of Miami and State of Ohio, have invented a new and Improved 5 Fruit-Drier, of which the following is a full, clear, and exact description.

The object of my invention is to provide an apparatus for drying all kinds of fruits and vegetables, and which can be conveniently operated without the danger of burning the material.

Reference is to be had to the accompanying drawings, forming a part of this specification, in which similar letters of reference indicate 15 corresponding parts in all the figures.

Figure 1 is a vertical longitudinal section of my improved drying-house. Fig. 2 is a vertical transverse section of the same. Fig. 3 is a detail section in larger size illustrating the 20 operation of transferring the crates from an upper to a lower chamber, and Fig. 4 is a detail section, showing the expansion-rods.

The house or stack A is formed of brick, concrete, or other suitable material, with a 25 furnace, B, in the lower portion, and with side and end walls, a a, and a top, b, that inclose the drying-chambers. It is also formed with a chimney, c. The flues d, that extend back and forth through the inclosed space, are connected with flues e in the back wall that lead 30 to the furnace B. These flues d d are formed by sheets or plates of iron set into the side walls, a a, and connected therein by vertical sections f, so as to form a continuous passage 35 from the furnace B to the chimney c. At each end the house is fitted with a door-frame, g, taking against the ends of the flues d and provided with one or more doors, h, that give access to the several chambers. The front and 40 back ends of the flues d are closed by blocks i, which are fitted so that they can be removed to allow of cleaning the flues. Across the front of the furnace are shafts k, provided with chain-wheels l, and at the rear of the furnace 45 are similar shafts, carrying chain-wheels m, for endless chains n that pass around the wheels l m. This arrangement is such that the upper portion of each chain moves upon the top of the flue or bottom of the chamber, and the 50 under portion of the chain passes through the chamber below. The flues are shortened al-

ternately at the forward and rear ends to give space for pivoted bars o, and beneath each bar o are inclined tracks p p', the track p' being pivoted at the upper end, as shown most 55 clearly in Fig. 3, by which the crates are transferred, as hereinafter described. Beneath the lower chamber is fitted an air-flue, q, opening at the side of the stack, where it is provided with a damper, q'. This air-flue 60 opens directly into the lower chamber and connects by an inclined passage with a flue, r, that opens into the upper chamber. The flue r is provided with a damper, r', and both dampers r' q' are fitted for movement by expansion-rods that operate automatically to open the dampers when the chambers become 65 too highly heated for the admission of air thereto. For containing the fruit to be dried I use crates s, that are provided with wheels 70 to run upon the bottom of the chambers, and with hinged and notched pawls s' at their upper sides for engaging with the chain n, whereby the crates are moved forward in the chambers. The shafts k are fitted outside the house 75 or door frame with gearing t, by which the chain can be caused to move alternately in opposite directions.

In the operation of the apparatus the crates containing the substance to be dried are placed 80 in the upper chamber through the doors h at the front and are carried forward by the chain to the rear. When they reach the pivoted bars o the forward wheels of the crate pass thereon, and the weight of the forward end of 85 the crate causes the bars to tip up to the position shown in dotted lines in Fig. 3, the rear ends passing up, one on each side of the crate s, so that the forward wheels pass upon the upper part of the track p, while the rear wheels 90 pass down the inclines o' upon the track p'. The crates then start in the opposite direction by gravity and are carried down the tracks p p' into the chamber below, where they are engaged by the chain therein and moved to 95 the opposite end, where their transfer takes place again, as before. In this manner the crates are kept in continuous or intermittent operation back and forth through the chambers, and are finally removed at the forward 100 end of the lower chamber. I prefer to use wooden crates, as that material will neither

poisen nor blacken the fruit. From the upper chamber a passage, *u*, connects with a vapor-escape tube, *u'*, partly within the chimney *e*, so that the vapors will be drawn off by the draft. When large quantities of fruit or vegetables are dried at once air may be forced through the house by a blower.

By the construction and arrangement, as described, the heat may be accurately regulated, so that there will be no danger of burning the material; and the rapidity of the movement of the crates through the chambers can be easily regulated, so that the material will be subjected to the heat for the required and proper length of time. The flues being formed by plates and their ends connected by the sections, the construction of the apparatus is greatly facilitated.

Having thus described my invention, I claim as new and desire to secure by Letters Patent—

1. The heating-flues *d* formed of horizontal

metallic plates arranged in the side walls, *a*, the vertical metallic sections *f*, having at each end a horizontal extension overlapping the ends of said plates, and the detachable blocks 25 *i*, as shown and described.

2. In drying-houses, the air-flues *q r*, in combination with the drying-chambers formed by a continuous back-and-forth flue from the furnace, substantially as described. 30

3. In drying-houses, the combination and arrangement, substantially as described, of the endless chains *n*, the flue or flues *d*, the pivoted bars *o*, and inclined tracks *p p'* at the ends of the flues for the purpose of automatically transferring the crates from the upper to the lower chamber. 35

ELIZABETH SHEETS.
